UNITED STATES PATENT OFFICE

MARIO VEDOVELLI, OF MILAN, ITALY

SKEINING IMPLEMENT

Application filed September 28, 1929, Serial No. 395,953, and in Germany October 11, 1928.

This invention relates to an implement for skeining or binding skeins or the like of yarn or thread by hand.

On the annexed drawings is shown by way of example an embodiment of the present invention, and

Figure 1 is a longitudinal section of the same on line 1—1 of Fig. 2;

Figure 2 is a plan view;

Figure 3 is a side view of the needle used to insert the binding thread or cord;

Figure 4 is a plan view of the same;

Figure 5 is a perspective view of the implement with the binding cord ready for use;

Figure 6 is a diagram of the skein binding.

The implement comprises a handle 1 having a bar 2 extending therefrom; aligned pins 3 are pivoted in said bar each of said pins having a cut 4 and a diametrical recess 5 having a lesser depth than cut 4 and at right angles thereto, the difference in depth of said cuts 4 and recesses 5 in the direction of axis of pins 3 being somewhat larger than the size of needle 12 (hereinafter described) in the same direction.

Each pin 3 is solid with a pinion 6 located on the face of bar 2 opposite that from which said pins 3 extend; said pinions 6 are engaged by a common rack bar 7 mounted to reciprocate in guides 8 and acted on by a spring 9 bearing on collar 10 solid with said rack bar 7 and on one of said guides 8.

In a casing 11 solid with bar 2 is mounted to move a needle 12 having at its front end a hook 13 adapted to engage the binding cord or thread as hereinafter described and protected by an enlarged head 14; at its opposite end said needle comprises a head 15 in which two projecting pins 16 and 17 are fastened, the first one of them reciprocating in a slot 18 of the casing and acting to guide the needle while the other one acts to impart to the needle the actuation of the actuating device hereinafter described.

Said needle is guided in its front portion in a slot 19 of the front wall of casing 11 and has on one side a projection 21 actuating the cord stretching member 22 which is fulcrumed at 22' and forced by a spring 42

against the needle projection 21 (Figs. 3 and 4).

A spindle 23 is pivoted in casing 11 and said spindle has two cams 24 and 25 solid therewith, cam 24 acting on a stud 26 of the rack bar 7 and cam 25 acting on pin 27 of a bar 28 mounted to reciprocate in guides 29 and having a return spring 30 which by one end engages one of guides 29 while its other end abuts on a collar 31 solid with bar 28. The free end of bar 28 is solid with a pin 35 on which is pivoted the first pair of a series of interpivoted arms 34 fulcrumed by links 33 on a pin 32 stationary in said casing 11; the last pair of said arms 34 is connected by links 37 with the needle actuating pin 17.

Spindle 23 has a pinion 38 solid therewith and meshing with rack bar 39 mounted to reciprocate by means of slot 43 and pin 44 and by tail 45 and bridge 46. The said rack bar 39 is actuated by operator by means of stud 40 extending outside of casing 11.

A cord stretcher 22 is pivoted at 22' in the casing 11; said stretcher extends to outside of said casing 11 through slot 41 and is acted on by spring 42.

At the end of bar 2 is fastened a spring clip 47 adapted to engage the front end 14 of needle 12 at the end of its forward stroke.

The shape and respective positions of cams 24 and 25 actuating rack bar 7 and bar 28 are such as at the beginning of rotation of spindle 23 firstly cam 24 is operative to move forward the said rack bar 7 and thereafter said cam is inoperative; cam 25 is inoperative during the period in which cam 24 is operative and then it drives bar 28 when rack bar 7 is stationary. For such a purpose the cam 24 comprises an initial spiral portion and a final circular portion while cam 25 has an initial circular portion and then a final spiral portion.

The operation is as follows assuming the implement to be in the conditions shown on the drawing, that is having needle 12 retracted and pins 3 with recesses 5 aligned with each other in the direction of the needle axis; then a skein binding cord or thread —*t*— is arranged in the manner shown in Fig. 5 with one end engaged in the hook 13 of 100

needle 12 and then the thread $-t$ is laid over stretcher 22 and finally said thread is located in recesses 5 of several pins 3.

Then the implement is located under the skein to be skeined or bound and pins 3 are inserted intermediate the threads or yarns of the same until their cuts 4 extend throughout from skein; during such an operation thread $-t$ passes under the skein yarns in its portions intermediate pins 3 while its portions engaged over recesses 5 of pins 3 lie over the upper skein surface, said thread $-t$ thus providing portions which are alternately under and above the skein.

Then operator moves stud 40 in the direction of arrow in Fig. 2 and thus he drives rack bar 39 which rotates pinion 38 with spindle 23 and cams 24 and 25; owing to the described arrangement of cams 24 and 25 and transmission ratio of parts, during the first period of rotation of said spindle 23 bar 28 is stationary and cam 24 actuates the rack bar 7 to cause said pins 3 to rotate through 90° ; thereafter the circular portion of said cam 24 holds said rack bar 7 stationary and pins 3 are thus held in a position to 90° with respect to illustrated one.

In view of such a movement of pins 3, cuts 4 of the same are now aligned in the path of needle 12 and the portion of thread $-t$ engaged in each recess 5 extends transversely to said path.

The last portion of rotation of spindle 23 and cam 25 causes bar 28 and its pin 35 to move and therefore the four bar gear 34 is extended to drive forward needle 12 which by its hook 13 drives the thread $-t$ and causes it to move with needle 12 through aligned cuts 4 of several pins 3 until said needle 12 and thread $-t$ engage the spring clip 47 which engages said thread $-t$; it being held engaged therein during the return stroke of said needle under action of return spring 30.

In this operation the end $-t'$ of thread or cord $-t$ which is driven by the needle hook 13 passes over the skein and under the portions of thread $-t$ which are engaged in recesses 5 of pins 3 and therefore are over and transverse the needle path the skein being thus bound as shown in Figure 6; thereafter portions $-t$ and $-t'$ of said binding thread are knotted with each other and the implement is removed from the completed skein.

Stretcher 22 acts to provide a supply of thread $-t$ corresponding with the needle stroke and to hold said thread stretched; when the needle is moved forward in the above described operation the needle projection 21 moves down said stretcher to cause it to pay thread $-t$ to said needle.

Of course the present invention is subject to modifications within the limits of appended

claims and particularly in the matter of the

ing gear as a lever gear or a pinion gear may be substituted for the four bar linkage 33, 34, 37.

What I claim as my invention and desire to secure by United States Letters Patent is:

1. A hand implement for skeining or binding skeins of yarn or thread comprising a support bar, a handle extending from said bar, means mounted to move in said support bar and adapted to extend through skein to be skeined and to carry a portion of binding thread, a needle mounted to move on said support bar to carry a portion of said binding thread to interengage with said first portion of the same, and hand-operable means for operating both said movable thread carrying parts and said needle.

2. A hand implement for skeining or binding skeins of yarn or thread, comprising a support bar, a handle extending from said bar, a row of aligned pins mounted to rotate in said support bar and each having an end binding-thread-receiving-recess and a cut transverse to and deeper than said recess, a needle mounted to move in said support bar to carry a portion of said binding thread to interengage with the portion of said binding thread lying in said pin recesses; means for rotating said pins to carry their said cuts in alignment with each other and with said needle, means for shifting said needle throughout said pin cuts and hand-operable means for operating said two last named means.

3. An implement for skeining or binding skeins of yarn or thread, comprising a support, a row of aligned pins mounted to rotate in said support and each having an end binding-thread receiving recess and a cut transverse to and deeper than said recess, pinions each solid with one of said pins, a needle mounted to move in said support to carry a portion of said binding thread to interengage with the portion of said binding thread lying in said pin recesses, a rack bar mounted to move in said support and engaging said pin pinions for rotating said pins to carry their said cuts in alignment with each other and with said needle, a cam having an initial operative portion and a subsequent inoperative portion and engaging said rack bar, means for shifting said needle and means operating said cam and needle shifting means.

4. An implement for skeining or binding skeins of yarn or thread comprising a support, a row of aligned pins mounted to rotate in said support and each having an end binding-thread receiving recess and a cut transverse to and deeper than said recess, a needle mounted to move in said support to carry a portion of said binding thread to interengage with the portion of the same dying in said pin recesses, a motion magnifying

- 5 said motion magnifying gear and having an initial inoperative portion and a subsequent operative portion, means operating said pins to carry their said cuts in alignment with each other and with said needle, and means actuating said cam and pin operating means.
- 10 5. An implement for skeining or binding skeins of yarn or thread comprising a support, a row of aligned pins mounted to rotate in said support and each having an end binding thread receiving recess and a cut transverse to and deeper than said recess, pinions each solid with said one of said pins, a needle mounted to move in said support to carry a portion of said binding thread to interengage with the portion of said binding thread lying in said pin recesses, a rack bar mounted to move in said support and engaging said pin pinions for rotating said pins to carry their said cuts in alignment with each other and with said needle, a first cam engaging said rack bar and having an initial operative portion and a subsequent inoperative portion, a motion magnifying gear operating said 20 needle, a second cam actuating said needle motion magnifying gear, said second cam being solid with the first named one and comprising an initial inoperative portion and a subsequent operative portion, the operative portion of each cam being in register with the inoperative one of the other cam, means actuating said cams and return means for said rack bar, motion magnifying gear and cam actuating means.
- 25 35. 6. An implement for skeining or binding skeins of yarn or thread, comprising a support bar, a handle extending from said bar, a row of aligned pins mounted to rotate in said support bar and each having an end binding thread receiving recess and a cut transverse to and deeper than said recess, a needle mounted to move in said support bar to carry a portion of said binding thread to interengage with the portion of said binding thread lying in said pin recesses, a clip member at the end of said pin row to engage the said binding thread at the end of the needle stroke, means for rotating said pins to carry their said cuts in alignment with each other and with said needle, means for shifting said needle throughout said pin cuts and hand operable means for operating said two last named means.
- 40 55. 7. An implement for skeining or binding skeins of yarn or thread, comprising a support, a row of aligned pins mounted to rotate in said support and each having an end binding thread receiving recess and a cut transverse to and deeper than said recess, a needle mounted to move in said support to carry a portion of said binding thread to interengage with the portion of said binding thread lying in said pin recesses, a stretcher for a supply of said binding thread, cooperating means on said needle and stretcher to cause said stretcher to pay off thread to said needle in its operative stroke, means for rotating said pins to carry their said cuts in alignment with each other and with said needle, means for shifting said needle throughout said pin cuts and means operating said two last named means.
- 45 8. An implement for skeining or binding skeins of yarn or thread, comprising a support consisting of a bar extending from a hollow handle, a row of aligned pins mounted to rotate in said bar and each having an end binding thread receiving recess and a cut transverse to and deeper than said recess, a needle mounted to move in said hollow handle to carry a portion of said binding thread to interengage with the portions of said binding thread lying in said pin recesses, means extending along said bar for rotating said pins to carry their said cuts in alignment with each other and with said needle, means in said hollow handle for shifting said needle throughout said pin cuts and means operating said two last named means.
- 50 9. An implement for skeining or binding skeins of yarn or thread, comprising a support consisting of a bar extending from a hollow handle, a row of aligned pins mounted to rotate in said bar and each having an end binding thread receiving recess and a cut transverse to and deeper than said recess, a needle mounted to move in said hollow handle to carry a portion of said binding thread to interengage with the portions of said binding thread lying in said recesses, means extending along said bar for rotating said pins to carry their said cuts in alignment with each other and with said needle, means in said hollow handle for shifting said needle throughout said pin cuts, a reciprocating stud projecting from said casing and operating said pin rotating means and needle shifting means.
- 55 10. An implement for skeining or binding skeins of yarn or thread comprising a support bar, a handle extending from said bar, means mounted to move in said support bar and adapted to extend through skein to be skeined and to carry a portion of binding thread, a needle mounted to move on said support bar to carry a portion of said binding thread to interengage with said first portion of the same, and hand-operable means for operating firstly said movable thread carrying parts and secondly said needle.
- 60 11. An implement for skeining or binding skeins of yarn or thread, comprising a support bar, a handle extending from said bar, a row of aligned pins mounted to rotate in said support bar and each having an end binding thread receiving recess and a cut transverse to and deeper than said recess, a needle mounted to move in said support bar to carry a portion of said binding thread to interengage with the portion of said binding

thread lying in said pin recesses, means for rotating said pins to carry said cuts thereof in alignment with each other and with said needle, means for shifting said needle throughout said pin cuts, and hand-operable means for operating firstly said pin rotating means and secondly said needle shifting means.

In testimony whereof I have signed my name to this specification.

10 MARIO VEDOVELLI.
